UNITED STATES PATENT OFFICE.

SAMUEL C. BENJAMIN, OF CHICAGO, ILLINOIS.

TUMBLER-WASHING MACHINE.

Application filed June 27, 1924. Serial No. 722,808.

This invention relates to new and useful improvements in tumbler washers and more particularly to a device for cleansing glasses and tumblers which are used in quantities

5 at soda fountains and other places of this character. The main object of the present invention is the provision of a machine for washing glasses and tumblers so that the interior and exterior thereof are cleansed at 10 the same time and wherein the water used for cleansing the tumblers is readily conveyed to a waste pipe.

Another object of the present invention is the provision of a device of this character 15 which includes a main supply tank, a support for the glasses movable in a vertical position and whereby the movement of the support will actuate means for supplying the cleansing fluid from the main tank to 20 upstanding spray pipes carried by the support for simultaneously spraying the cleansing fluid upon the exterior as well as the interior of the glasses or tumblers being cleansed.

25 With the above and other objects in view the invention consists in the novel features in construction, the combination and arrangement of parts hereinafter more fully set forth, pointed out in the claims and shown 30 in the accompanying drawings in which:—

Fig. 1 is a vertical sectional view of a tumbler washer constructed in accordance with my invention.

Fig. 2 is a detail plan view.

35 Fig. 3 is a detail section taken on the line 3—3 of Fig. 1.

The main embodiment of my invention 40 comprises a supply tank 1, supported upon suitable standards 2 and mounted upon the upper end of the tank 1 is a removable cover 3 having an upstanding annular flange 4 extending circumferentially of the perimeter of the cover as illustrated in Fig. 1.

The cover member 3 is provided with out- 45 standing annular flanges 5 which are preferably arranged so as to be fitted upon the interior of the tank 1 and frictionally engage the inner walls of the tank 1 at a point adjacent the upper open end of the same as 50 shown in Fig. 1 so as to retain the cover member in position upon the open end of the tank. The upstanding flange 4 is provided with inwardly extending lugs 6 and resting upon these lugs is a drain plate 7 hav- 55 ing a plurality of perforations 8 therein to permit the liquid to pass into the upper sur-

face of the cover 3 and this liquid is then drained off through an outlet pipe 9 which extends through the cover at any convenient location.

60 Suspended from the top 3 are the guide rods 10, said rods having their upper ends extended through the top portion 3 and provided with nuts 11 which are threaded upon the upper ends of the rods to retain them in 65 position. The lower ends of the rods are reduced in size as at 12 and mounted upon the reduced portion are the plates 14 which support a supply cylinder 15, said cylinder 70 in the present instance being formed integral with the lowermost plate 14 and this plate being secured upon the rods by means of the nuts 16. The cylinder 15 is provided upon its upper end with arcuate slots 17 to 75 permit the liquid contents of the tank 1 to enter the cylinder.

80 Mounted for reciprocating movement within the cylinder 15 is a plunger 18 having a tubular member 19 attached thereto and extending through the central portion of the plunger, said tubular member extending upwardly between the rods 10 and projecting through a guide sleeve 20 formed at the central portion of the cover member 3. The upper end of the tubular member 19 is 85 threaded and mounted thereon is a supporting disc 21, said disc having a plurality of extensions 22 radiating from the center of the disc, and these extensions are preferably hollow forming a passage 23 in each of the extensions, said passages communicating with the central enlarged portion of the disc forming a direct communication with the tubular member 19.

90 The passages 23 which extend through the extensions 22 open outwardly at the outer ends of the extensions and are normally closed by means of the removable plugs 24. The outer ends of the extensions 22 are provided with transverse passages extending below and above the main passage 23, the lower passage 25 of each rib being normally closed by means of a removable plug 26. The upper passage 27 extending through a supporting sleeve 28 and mounted within each of these supporting sleeves is an upright tube 29, the upper end of which is provided with perforations 30, said perforations being formed upon the inner side of the tube or that side which faces the center of the supporting disc, and furthermore these perforations 30 are formed in the tubes 29 at a point 100 105 110

adjacent the outer ends thereof as clearly illustrated in Fig. 1 whereby the passage of cleansing fluid up through the tubes 29 will be discharged through the perforations toward the center of the supporting disc.

Mounted at the center of the disc 21 and having communication with the upper end of the tube 19 and the passages 23 is a conveying tube 31, this tube is vertically disposed 10 the same as the tubes 29 but is somewhat shorter than the tubes 29 and is provided within its upper end with perforations 32 whereby cleansing fluid is supplied to the interior of the glass or tumbler being 15 cleansed.

Mounted upon the tube 19 with its lower end arranged within a guide 33 is a coil spring 34, the upper end of which is fitted into a guide collar 35, said collar being secured to the tube 19 at a pre-determined distance from the cylinder 15, whereby the tension of the spring 34 will normally retain the plunger 18 in its raised position against the uppermost plate 14 as shown in Fig. 1 20 and from this it will be apparent that when a glass or tumbler is placed upon the supporting disc 21 and downward pressure exerted upon the tumbler, the tube 19 will be reciprocated, forcing the plunger 18 downwardly within the casing 15, causing the contents of the casing to move upwardly through the tube 19 out through the passages 23 and through the tubes 29 and 31 whereby the 25 cleansing fluid will be sprayed through the medium of the perforations 30 and 32 simultaneously upon the interior and exterior of the glass or tumbler being cleansed, the used fluid passing downwardly through the openings 36 in the disc 21 and through the perforations 8 on the drain plate 7 onto the upper 30 face of the cover member 3 from whence it is conveyed through the outlet pipe 9.

From this it will be apparent that the 35 cleansing fluid is used only once and that when the contents of the main supply tank 1 has been emptied of its contents it is necessary to replenish the supply for further 40 cleansing.

In order to prevent the cleansing fluid 45 from entering the sleeve 20 around the tube 19 a housing 37 is attached to the under surface of the disc 21 and surrounds the tube 19 at a point below the disc, said housing being provided at its lower end with a flared edge 50 as at 38 so as to guide the cleansing fluid away from the sleeve 20 and tube 19 and prevent any of the same from entering the sleeve 20 and interfering with the operation of the device or prevent the return of the 55 fluid into the main supply tank 1.

From the above it will be apparent that I 60 have provided a device of this character wherein the glasses or tumblers being cleansed may be quickly and readily placed 65 in position upon the supporting disc 21 and

by a downward pressure, the cleansing fluid will be supplied simultaneously to the interior and exterior of the article being cleansed, and the fluid after once being used will be conveyed to a waste pipe and be prevented from being returned to the supply within the tank 1.

While I have shown and described the preferred form of my invention I wish it to be understood that various changes and alterations may be carried out during the manufacture of the same without departing from the spirit of the invention or the scope of the appended claims.

Having thus described my invention what I claim is:

1. In a tumbler washer, a tank comprising a fluid reservoir and having an open upper end, a cover for the open end of the tank having a drain plate thereon, rods suspended from said cover and drain plate carrying a cylinder having an inlet in the upper side thereof, a piston adapted for reciprocation in said cylinder, a tubular member mounted for vertical sliding movement in said cover and drain plate and secured to and extending through said piston so as to comprise an outlet for said cylinder, spring means disposed around and adapted to urge said tubular member upwardly, said piston being adapted to engage the upper wall of said cylinder to limit said upward movement, and a fluid distributing member carried on the upper end of said tubular member above said cover and drain plate and adapted to receive a tumbler, downward movement of said tumbler, distributing member, tubular member, and piston forcing fluid from said reservoir and said cylinder through said tubular member and distributing member against said tumbler.

2. In a tumbler washer, a tank, a drain plate providing a cover for the open end of the tank, a cylinder mounted within the tank adapted to be open at its upper end, a piston adapted for operation in the cylinder, a tubular member open at both ends and projecting through the drain plate and having its lower end in communication with the cylinder and adapted to carry the piston, a tumbler support carried by the upper end portion of the tubular member having vertically extending tubular columns provided with openings therein directed toward said tumbler support, said tumbler support having openings therein directed toward said first mentioned openings and arranged so as to embody a passage adapted to extend therethrough, said passage and said tubular columns being in communication with said tubular member, said tumbler support being arranged to impart downward movement to the tubular member and piston by imposed weight thereon, spring means disposed around said tubular member between a collar

thereon and said cylinder normally retaining said tubular member and piston in their uppermost positions, and members suspended from the drain plate within the tank 5 for bodily supporting the cylinder, piston, tubular member, and tumbler support so as to permit said just mentioned parts to be bodily removed from the tank when the

drain plate is removed from covering position, said downward movement forcing fluid 10 from said tank through said tubular member and openings in the tumbler support and vertical columns against a tumbler mounted on said tumbler support.

In testimony whereof I affix my signature.
SAMUEL C. BENJAMIN.
